FILLING CUTTING MEANS

Carl D. Brown, Hopedale, Mass., assignor to
Draper Corporation, Hopedale, Mass., a corpora-
tion of Maine

Application January 21, 1944, Serial No. 519,117

3 Claims. (Cl. 139—196)

The present invention relates to shuttles for use in automatic looms and, as illustrated herein, relates more particularly to an improved cutting means mounted in one wall of the shuttle.

In certain types of looms, the outgoing filling thread is cut loose to the shuttle eye so that the ejected bobbin or filling carrier can unthread the eye. One form of thread cutter which is particularly well adapted for this purpose includes a flat plate carried by the front wall of the shuttle and located close to the side delivery eye so that the filling thread extends across the plate and is in the path of movement of a thread cutter when the thread cutter moves toward the shuttle during the filling carrier transferring operation.

Under some conditions, the filling may be slack and as a result the filling will sag and may fall below the thread cutter and consequently will not be severed. As a result, the shuttle will not be unthreaded and the outgoing filling end will be carried into the shed on the next pick forming an extra end which forms a defect in the cloth.

One object of the present invention is to provide a shuttle having an improved thread cutter by the use of which the above mentioned difficulty will be overcome. To this end, the thread cutter is provided with means which will support the filling thread and prevent its sagging below the thread cutter thus insuring that each outgoing filling thread will be severed during the transferring operation.

With the above and other objects and features in view, the invention will now be described with particular reference to the accompanying drawing which illustrates preferred embodiment of the invention in which:

Fig. 1 is a view in front elevation of a shuttle in which the present invention is embodied:

Fig. 2 is a view in section taken along the line II—II of Fig. 1;

Fig. 3 is a perspective view of the cutting member;

Fig. 4 is a view in section taken along the line IV—IV of Fig. 3;

Fig. 5 is a view in section taken along the line V—V of Fig. 3; and

Fig. 6 is a view in section taken along the line VI—VI of Fig. 1.

The shuttle 10 shown in the drawing is generally of usual construction and includes a shuttle body 12 having the usual filling carrier recess 14 and a cavity 16 in which the threading block 18 is supported. The shuttle body 12 may, as illustrated, be provided with vulcanized fiber covered

front, back and bottom walls **20**, **22**, **24**, respectively. The threading block **18** is maintained in position by a bolt **26**. The threading block is of usual construction and, as illustrated, comprises front and rear walls **28**, **30** forming between them a usual longitudinal thread passage. Tension pads **34** are mounted in said passage adjacent to the inner end thereof. The thread passage **32** communicates with a side delivery eye **36** which is provided with vertical thread engaging posts **38** and **40**.

The bolt 26 is threaded into a rearwardly extending boss 42 of a flange nut 44. The flange nut 44 fits into an opening formed in the fiber front wall 20 and into a recess formed in the shuttle body 12. Thus the flange nut 44 is adequately supported over its entire extent and cannot move when clamped in position by the bolt 26.

which clamped in position by the bolt 20. In the present construction, the flange nut 44 is provided with a lateral extension 46 having a flat forward exposed face located in a plane offset rearwardly from the forward surface of the flange nut 44. The flange nut 44 is provided with a generally horizontally disposed groove 48 in which the filling thread runs when the shuttle is picked from the left hand shuttle box. The groove 48, as shown most clearly in Figs. 4 and 5, is so shaped that a downwardly and rearwardly inclined shelf 50 is formed which supports the filling and permits the filling to be maintained at a level sufficiently high so that some portion of the filling will be above the lower edge of the extension 46. Under most conditions, the filling thread will be under sufficient tension so that it will extend substantially horizontally across the extension 46. Under some conditions, due, for example, either to overrunning of the filling or to slight rebound of the shuttle the filling may sag across the plate or extension 46 but will still be located in position to be cut. As shown in Fig. 5, the groove 48 is quite deep near the side delivery eye and then gradually diminishes in depth until it reaches the left hand edge 52 of the nut 44. The groove 48, however, is deep over a sufficient length to provide adequate support for the filling and the inherent stiffness of the filling will cause it to extend out over the extension 46 a distance sufficient to be engaged by the other cutting element.

50 The forward face of the extension 46 is located rearwardly of the forward face of the flange nut 44 and thus the running filling does not contact said extension. Thus even if said surface is scarred, it will not contact the filling thread and 55 cause the fibers thereof to be cut or torn. The

present construction, therefore, not only supports the filling thread in position to be cut but also prevents undesired contact of the filling thread with the cutting surface of the extension 46 thus preventing undesired cutting or tearing of the fibers of the filling.

Having thus described my invention what I claim as new and desire to secure by Letters Patent of the United States is:

1. In a shuttle for automatic looms having a threading block, a side delivery eye and a bolt for securing the threading block in position, a plate having a threaded opening for receiving said bolt and located close to said side delivery eye, said plate having a substantially horizontal groove therein in which the filling runs during operation of the loom, and an extension on said plate having a forward plane surface against which the filling is cut, said forward surface of said extension being offset rearwardly from the forward face of said plate to prevent engagement of the running filling with said forward surface of said extension.

2. In a shuttle for automatic looms having a threading block, a side delivery eye and a bolt for securing said threading block in position, a plate located closed to the side delivery eye hav-

ing a threaded opening in which said bolt is threaded, said plate having a substantially horizontal groove therein, having one wall thereof inclined downwardly and rearwardly to constitute a shelf on which the running filling is supported, and an extension on said plate having a forward plane surface against which the filling is cut, said forward surface of said extension being offset rearwardly from the forward face of 10 said plate to prevent engagement of the running filling with said forward surface of said extension.

3. In a shuttle for automatic looms having a threading block, a side delivery eye and a bolt 15 for securing said threading block in position, a plate located close to the side delivery eye having a threaded opening in which said bolt is threaded, said plate having a substantially horizontal groove therein, having one wall thereof inclined downwardly and rearwardly to constitute a shelf on which the running filling is supported, and a lateral extension on said plate having a flat surface offset rearwardly from the forward surface of said plate and against which the filling is 20 cut to prevent undesired engagement of the running filling with said plate.

CARL D. BROWN.
